UNITED STATES PATENT OFFICE

2,283,239

FINISHING MACHINE

Laurence E. Topham, Wenham, and Edwin W. Smith, Beverly, Mass., assignors to United Shoe Machinery Corporation, Borough of Flemington, N. J., a corporation of New Jersey

Application May 17, 1940, Serial No. 335,756

10 Claims. (Cl. 12—78)

This invention relates to finishing machines and is illustrated herein as embodied in an edge setting machine of the type disclosed in United States Letters Patent No. 2,190,810, granted February 20, 1940, on application of L. E. Topham.

Edge setting machines are customarily provided with two differently-shaped burnishing tools which are alternately used to operate on different sections of the sole edge, these tools being carried in a holder which can be released from the customary oscillating shaft for rotation to interchange the tools. It is also customary to provide tool heating means such as gas jets, for example, which are located on opposite sides of the tool holder adjacent to the path traversed by the tool when the tool holder is coupled to the oscillating shaft. As the adjustment of the heating means is rather critical, the operator usually adjusts it at the beginning of the day's work and then leaves it set while the machine is in operation. This results in the tools becoming overheated when the machine is temporarily idle for one cause or another. With this in view, a further feature of this invention consists in the provision of means for moving the tool holder to a position where the tools are removed from heating proximity to the heating means and for holding them in that position while the machine is idle. As illustrated, that means consists of a stop which is movable into the path traversed by the tool holder when the tools are shifted, the stop being arranged to interrupt the rotation of the tool holder in a position where both tools are spaced a substantial distance from the heating means.

The illustrated machine is provided with tool holder shifting means of a type now in general use which includes oppositely-inclined surfaces on the oscillating shaft that extend between the two tool holder lug receiving notches. When the tool holder is rotated to interchange the tools, the lugs on the tool holder ride down the inclined surface until they reach the lug receiving notches. When the rotation of the tool holder is interrupted by the above mentioned stop, the lugs are held stationary while the shaft continues to oscillate with the result that wear will soon develop between the lugs and the inclined surfaces at the stopped position of the tool holder. With this in view, it is a further object of this invention to prevent excessive wear between the tool holder lugs and the inclined surfaces on the oscillating shaft at the stopped position of the tool holder. To this end, the illustrated stop is swingably mounted and is provided with a

shouldered portion which is arranged to engage beneath a portion of the tool holder and to move the tool holder outwardly from the oscillating shaft when it stops the rotation of the tool holder. This outward movement of the tool holder separates the lugs on the tool holder from the inclined surfaces on the oscillating shaft and thus eliminates wear between those parts. In addition, it provides an arrangement for holding the tool carrier stationary so that the tool-operated clamping means may be released and the tools changed. This last feature is important as obviously it would be almost impossible to release the tool-operated clamping means while the tool holder was vibrating at a high rate of speed.

With the above and other objects in view, the invention will now be described with reference to the accompanying drawings and will be pointed out in the appended claims.

In the drawings,

Fig. 1 is an angular view of a portion of an edge setting machine embodying features of this invention;

Fig. 2 is a fragmentary elevation showing details of the back stop mechanism which prevents reverse rotation of the tool holder during the tool shifting operation;

Fig. 3 is an elevational view looking toward the left side of the mechanism shown in Fig. 1 and illustrating the position of the parts at the beginning of the operation of the stop member; and

Fig. 4 is a view similar to Fig. 3 showing the position of the parts when the stop member is in the position in which it holds the tool holder while the tools are idle.

In the illustrated construction, 10 (Fig. 4) indicates an oscillating shaft which is rotatably mounted in a bearing 12 and is oscillated back and forth at a high rate of speed by a driving mechanism of the type illustrated in the above mentioned patent to Topham No. 2,190,810. Slidably and rotatably mounted in the shaft 10 is 45 a spindle 14 which projects from a tool holder 16, the tool holder being urged inward in the direction of the shaft 10 by a spring 18 which is mounted in a cylindrical opening in the spindle 14. The shaft 10, bearing 12, spindle 14, and spring 18 correspond respectively to the members 34, 39, 104, and 122 in the machine disclosed in the Topham patent (see Fig. 4 thereof).

The oscillating shaft 10 is provided with a comparatively large head 20 having a pair of oppositely-disposed notches 22, 24 (Fig. 1) which

form part of the driving connection that causes the tool head to move in unison with the oscillating shaft. The remainder of the driving connection is formed by a pair of lugs 26, 28 which depend from the tool receiving portions of the tool holder 16 and are held in the notches 22, 24 by the action of the spring 18. Attached to and forming a part of the head 20 are a pair of oppositely-inclined arcuate plates 30, 32 which extend obliquely to the direction of oscillation of the shaft, the plates being located so that their ends form the side walls of the notches 22, 24. These plates are attached to the head 20 by screws 34 and form runways down which the bottoms of the lugs 26, 28 ride when the tools are shifted.

The tool holder is rotated through 180° to change the tools by a shifting lever 36 which is fulcrumed on a pin 38 mounted on a bracket 40 which extends outwardly from the bearing 12. The lever 36 has a pair of spaced arms 42, 44 which extend inwardly along opposite sides of the tool head to points behind the notches 22, 24 and at their inner ends are provided respectively with rollers 46, 48 which are located behind inclined faces 51 on flanges 50 formed on the outer ends of the lugs 26, 28 and corresponding to the oblique faces 66 provided for a similar purpose in the machine illustrated in Letters Patent of the United States No. 1,986,968, granted January 8, 1935, on an application filed in the name of William Hamann. When it is desired to change the tools, the shifting lever is rocked in a counterclockwise direction (as viewed in Fig. 2) causing the rollers 46, 48 to strike the inclined faces 51 on the flanges 50 and to move the tool holder outwardly against resistance of the spring 18 until the lugs 26, 28 are clear of the notches when the action of the rollers 46, 48 on the inclined faces of the flanges 50 will move the tool holder in a clockwise direction, as viewed in Fig. 1, until the bottoms of the lugs 26, 28 are placed on the high ends of the inclined plates 30, 32. The tool holder will then be shifted through 180° in a manner which is fully described in the above mentioned patent to Hamann No. 1,986,968.

The tool holder continues to oscillate at a high rate of speed as the lugs 26, 28 are moved outwardly from the notches in the head of the oscillating shaft and occasionally, as the lugs reach their outer limit of movement, they receive a counterclockwise impulse of sufficient strength to cause the inclined faces on the flanges 50 to ride up over the rollers 46, 48 and move the lugs 26, 28 backwardly onto the wrong plates. To prevent this undesired backward movement of the tool holder during the shifting operation, the arm 42 is provided with a finger 52 which extends behind a laterally projecting rib 54 which is formed on the outer face of the flange 50. The finger 52 (Fig. 2) is located sufficiently far behind the rib 54 so that it will not interfere with the movement of the rib when the lugs are seated in the notches in the oscillating shaft, and is of sufficient height so that it extends behind the rib 54 at all times during the movement of the lugs out of the notches. Thus the finger 52 positively prevents backward or counterclockwise movement of the tool holder lugs over the rollers 46, 48 inasmuch as the rib 54 strikes the finger before the lugs pass over the high points of the rollers and stops their backward movement.

The lugs 26, 28 on the tool holder each have an outwardly extending portion which terminates in a cylindrical head having a downwardly- and

inwardly-inclined opening designed to receive a tool carrier spindle. Slidably and rotatably mounted in these recesses are tool carrier spindles 56, 58 which have flat surfaces 60 formed near their inner ends and enlarged heads 62, 64 formed on their outer tool engaging ends.

The latches now in general use for holding tools on the tool carriers are of a yielding character which permit considerable play between those members when they are oscillated at the high speeds used in machines of the type disclosed in the above identified Topham patent with the result that considerable wear develops between the tool carriers and the tools. As the overall movement of the tool is very small, being in the neighborhood of $\frac{1}{16}$ of an inch, eventually the wear between the tool and the tool carrier reduces the movement of the tool to a negligible amount, rendering the tool useless so that it must be discarded. This difficulty is overcome by the tool clamping device illustrated herein which holds the tool firmly on the tool carrier and prevents relative movement between those members when they are oscillated at a high rate of speed.

The clamping device consists of a shoulder 66 which extends from one side of the enlarged tool carrier head where it is adapted to engage one side of a burnishing tool 68. The opposite side of the tool 68 is engaged by the roughened face 60 of a plate 70 which is fastened on the tool carrier head by a screw 72. The inner face of the plate 70, which is adjacent to the tool carrier head, is recessed from a point a slight distance beyond the end of the head adjacent to the tool to the rib 74 on the end of the plate. When the screw 72 is tightened, the plate 70 will fulcrum about the rib 74 causing the roughened part of the plate to press the tool against the shoulder 66 thereby clamping the tool between them so that there can be no relative movement between the tool and the tool carrier when the tool holder is oscillated.

The tool carrier spindles 56, 58 are permitted a limited amount of rotative and axial movement in their bearings which allows them to follow the changes in curvature occurring about the sole edge. Inward movement of the spindles is resisted by balls 76 (Fig. 1) carried by the outer ends of springs 78, the balls being located behind the inner ends of the tool carrier spindles and being urged in an outward direction by the springs. Rotation of the tool carrier spindles is resisted by the lower ends of a pair of depending arms 80, 82 which extend from a light plate of spring material 84 and engage the flat surfaces 60 formed on the inner ends of the spindles. The plate 84 extends transversely to the arms 80, 82 and is provided at its opposite ends with openings that fit around the ends of posts 86, 88 which also serve as mounting means for the springs 78. By using the light plate of spring material 84 and locating it centrally of the tool holder, the relatively heavy eccentrically-located spring-pressed latches, which have heretofore been used yieldingly to resist rotation of the tool carrier spindles, have been eliminated thereby reducing the inertia of the tool holder and the vibrations caused by the frequent reversals in the direction of its motion.

The means for clamping the tools to the tool carriers and the means for locating the carriers centrally in the tool holders form the subject matter of and are claimed in an application for United States Letters Patent Serial No. 400,608,

filed July 1, 1941, in the name of Edwin W. Smith.

The tool head is surrounded by the usual housing 90, indicated partly by a dotted outline, in Figs. 1 and 4, which is provided with an opening in one side for the tool shifting lever. Located on the side of the housing 90 opposite to the shifting lever opening is a bar 92 which is arranged to interrupt rotation of the tool holder at a point about midway between the notches 22, 24 and to keep the tool holder in that position where the tools are well away from the tool heating means so long as the tool head is not in use and thereby preventing the tools becoming overheated.

The bar 92 is pivoted on a stud 100 and hangs in an out-of-the-way position (see broken-line position, Fig. 3) until it is desired to remove the tools from proximity to the tool heating means during the time the machine head is to be idle when the bar is swung up into the path of rotation of the tool carrier where it engages a shouldered pin 94 (Fig. 4) which juts out from the housing 90. When the bar is in this position, it will stop the rotation of the tool holder at a point where the tools are well removed from the usual heating means, herein illustrated as the gas jets 104, 106, which are located on opposite sides of the tool holder above and below the notched portion of the head of the oscillating shaft.

To prevent wear between the bottom surfaces of the lugs 26, 28 and the inclined plates 30, 32 on the head of the oscillating shaft while the tool holder is engaged by the bar 92, the bar is provided with a shouldered end portion which comprises a finger 96 and a rounded knoblike projection 98. When it is desired to move the tool holder to its inoperative position, the bar 92 is elevated, as shown in Figs. 1 and 3, so that its shouldered portion is located in the path of the tool carrier on the lug which is moving down the inclined plate 32. Thus the flange 66 on the tool carrier strikes the finger 96 causing the bar to rotate about its pivot 100, and as the bar rotates, the projection 98 engages beneath the tool 68 and the flange 66 and moves the tool holder outwardly from the head 20 of the oscillating shaft against the pull of the spring 18. The bar 92 rotates with the tool holder until the center line 102 of the bar moves past the center line of the spring 18 when the bar engages the shouldered pin 94, a line 101 parallel to the center line of the spring being shown in Fig. 4. The bar will be held in this position by the pull of the spring 18 which acts through the tool carrier inwardly against the shoulder portion of the bar and tends to rotate it in a counterclockwise direction, as viewed in Fig. 4, thereby holding the bar against the pin 94. When the tool holder is in its inoperative position (Fig. 4), the bottom faces of the lugs 26, 28 are well clear of the inclined plates.

The bar 92, in addition to holding the lugs on the tool holder away from the inclined plates on the oscillating head while the tools are not in use, also holds the tool carrier stationary so that the screws 72 can be backed off, releasing the clamping plates 10 and permitting the tools to be changed while the driving mechanism continues to operate. Obviously this change could not be easily made while the tool holder is in contact with the oscillating shaft as it would be very difficult, if not impossible, to hold a wrench in engagement with the rapidly moving heads

of the screws 72. This is an important feature as most edge setting machines are of the twin type in which two setting stations are provided and if the machine had to be shut down each time the tools were changed both stations would be put out of operation while the change was being made.

Tool changes are effected by backing of the screw 72 of the tool carrier opposite to the one engaged by the bar 92 and making the desired change; then, if it is desired to change the tool which is engaged by the bar, the tool holder is released from the bar, rotated through 180° and the opposite tool carrier engaged by the bar as it comes around, and the tool holder again moved to its inoperative position, whereupon the second tool change can be made.

To release the tool holder from its inoperative position, the operator moves the tool holder in a counterclockwise direction or downwardly as viewed in Fig. 4, until the tool carrier is clear of the bar 92 when the bar drops to its out-of-the-way position, permitting the machine to complete the shifting operation which was interrupted by the bar.

Having thus described our invention, what we claim as new and desire to secure by Letters Patent of the United States is:

1. In a finishing machine, an oscillating shaft, a tool holder having a plurality of tools rotatably mounted on said shaft, means for connecting the tool holder to the shaft to cause one of the tools to be secured in an operative position for oscillation with the shaft, means for heating the tool in operative position, means for rotating the tool holder in the interchange of tools, and means for stopping the rotation of the tool holder in a position where the tools are removed from the heating means.

2. In a finishing machine, an oscillating shaft, a tool holder for a pair of tools rotatably mounted on said shaft, means for connecting the tool holder to the shaft to oscillate therewith, heating means disposed in proximity to both tools when the tool holder is connected to the shaft, means for rotating the tool holder to interchange the tools, and means for stopping the rotation of the tool holder in a position where the tools are removed from heating proximity to the heating means.

3. In a finishing machine, an oscillating shaft, a tool holder rotatably mounted on said shaft, means for connecting the tool holder to the shaft to oscillate therewith, heating means disposed in proximity to the tools in the tool holder when the holder is connected to the shaft, means for rotating the tool holder to interchange the tools, and a latch mounted on the machine adjacent to the tool holder and arranged for movement into and out of the path of the rotating holder, said latch when located in the path of the rotating holder being arranged to stop the rotation of the holder in a position where the tools are removed from proximity to the heating means.

4. In a finishing machine, an oscillating shaft, a tool holder for a pair of tools rotatably mounted on said shaft, means for connecting the tool holder to the shaft for oscillation therewith, heating means disposed in proximity to both tools when the tool holder is connected to the shaft, means for rotating the holder to interchange the tools, and a stop arranged for movement into the path of the rotating holder to interrupt the rotation of the holder in a position where the tools are removed from proximity to

the heating means, said stop comprising a pivoted bar and an abutment arranged to limit the movement of the bar in the direction of rotation of the tool holder.

5. In a finishing machine, an oscillating shaft, a holder for a plurality of tools rotatably mounted on said shaft, means for rotating the tool holder about the shaft to interchange the tools, and pivoted means for stopping the rotation of the tool holder between the normal tool positions and for disconnecting the tool holder from the shaft so that the movements of the oscillating shaft are not transmitted to the tool holder.

6. In a finishing machine, an oscillating shaft, a holder for a plurality of tools rotatably mounted on the shaft, said shaft and said holder having cooperating faces oblique to the direction of oscillation of the shaft, means for holding said faces in abutting relation whereby the oscillations of the shaft in one direction are utilized to rotate the tool holder about the shaft to cause an interchange of tools, and a pivoted member arranged to stop the rotation of the tool holder between normal tool positions and to move the cooperating faces on the shaft and the holder out of abutting engagement with each other.

7. In a finishing machine, an oscillating shaft, a holder for a plurality of tools rotatably mounted on said shaft, yieldable means for urging the tool holder toward the shaft, tool heating means, means for rotating the tool holder to interchange the tools, and a pivoted member arranged to stop the rotation of the tool holder in a position where the tools are removed from proximity to the heating means and to move the tool holder away from the oscillating shaft to disconnect the shaft from the holder and prevent oscillating movements of the shaft being transmitted to the holder.

8. In a finishing machine, a shaft arranged to oscillate at a high rate of speed, a holder for a plurality of tools rotatably mounted on said shaft, said shaft and said tool holder having cooperating faces oblique to the direction of oscillation of the shaft, yieldable means for holding said faces in abutting relation whereby the oscillations of the shaft in one direction are uti-

lized to rotate the holder about the shaft to cause an interchange of tools, a plurality of finishing tools connected to said holder by clamping means, and a pivoted member arranged to stop the rotation of the tool holder between normal tool positions and to move said tool holder away from the shaft to a position where the cooperating faces on the shaft and the tool holder are out of contact with each other and the holder is held stationary so that the clamping means can be released and the finishing tools changed.

9. In a finishing machine, an oscillating shaft, a tool holder rotatably mounted on said shaft, driving connections between the shaft and the tool holder comprising an extension on the tool holder and oppositely-disposed notches in the shaft, the surfaces on the portions of the shaft which connect the notches being oppositely-inclined and extending obliquely to the direction of oscillation, means for lifting the extension on the tool holder out of a notch and placing it on the higher end portion of the adjacent inclined surfaces, and means for positively preventing the tool holder extension from moving backwardly onto the lower end portion of the inclined surface on the opposite side of the notch.

10. In a finishing machine, an oscillating shaft, a tool holder rotatably mounted on said shaft, driving connections between the shaft and the tool holder comprising extensions on the tool holder and notches in the shaft, the surfaces on the portions of the shaft which connect the notches being oppositely-inclined, a tool holder shifting lever for lifting the extensions on the tool holder out of the notches and placing them on the higher end portions of the adjacent inclined surfaces, and means for preventing the tool holder extensions from moving backwardly onto the lower end portions of the inclined surfaces on the opposite side of the notches, said means comprising a projection on the shifting lever located closely adjacent to and behind a cooperating surface on the tool holder.

LAURENCE E. TOPHAM.
EDWIN W. SMITH.
